WHIPPING AND BEATING DEVICE

Albert E. Thinglum, Sioux Falls, S. Dak., assignor
of fifty-one one-hundredths to A. F. Larson,
Sioux Falls, S. Dak.

Application December 26, 1939, Serial No. 311,925

2 Claims. (Cl. 259—132)

My invention relates to improvements in whipping and beating devices and has as one of the principal objects thereof the provision of a device of the above-described character so constructed and arranged whereby the agitators or beaters may be readily removed so that they, with their associated parts, may be thoroughly cleaned to effect sanitification.

Another object of my invention is to provide a device of the above-described character which is simple in construction, durable in use, efficient in operation and economical in manufacture.

Other objects and advantages will be apparent from the following description, appended claims and annexed drawings.

Referring to the drawings wherein like reference characters designate like parts throughout the several views:

Figure 1 is a front elevation of my invention.

Figure 2 is a side elevation thereof.

Figure 3 is a detail sectional view taken on the line 3—3 of Figure 2.

Figure 4 is a detail perspective view of the latch member.

Figure 5 is a detail perspective view of one of the upper ends of the lower frame section.

Figure 6 is a detail sectional view taken on the line 6—6 of Figure 1.

Figure 7 is a top plan view of the outer agitator.

Figure 8 is a top plan view of the inner agitator.

Figure 9 is a detail perspective view of the member effecting detachable connection between the agitators and the means for rotating said agitators.

Figure 10 is a front elevation of a modified form.

Figure 11 is a side elevation of said modified form.

Figure 12 is a sectional view taken on the line 12—12 of Figure 11.

Figure 13 is a sectional view taken on the line 13—13 of Figure 12.

Figure 14 is a detail perspective view of one of the upper ends of the lower frame section of the modified form.

Figure 15 is a detail perspective view of a modified form of crank arm bearing.

In practicing my invention, as illustrated in Figures 1 to 9 inclusive of the drawings, I provide a frame 5 equipped with upper and lower detachable frame sections 6 and 7 respectively. The upper frame section 6 comprises a pair of spaced side walls 8 having their lower ends integrally connected together by a transverse lower wall 9 and their upper ends fashioned to define a handle

10. One of the side walls 8 is fashioned, between its upper and lower ends, with a pair of spaced arms 11 extending towards the other side wall and constituting bearings 11 through which are journaled upper and lower ends of a vertically disposed shaft 12.

The upper and lower ends of the shaft 12, above and below said bearings 11, have mounted thereon frustum-shaped elements 13 and 13a respectively frictionally engaging a similar shaped element 14 interposed therebetween and coaxing therewith to constitute a frictional drive means for said elements 13 and 13a. The element 14 is fixed to the inner end of a crank arm 15 provided with a handle 15a and which is journaled in a bearing 16 carried by one of the side walls 8.

Sleeved about the bearing 16, between the element 14 and the adjacent side wall 8, is a coil spring 17 urging said element 14 into engagement with the elements 13 and 13a whereby operation of the crank shaft 15 serves to impart rotation to said elements 13 and 13a. The upper element 13 is keyed to the shaft 12 for effecting rotation of the latter while the lower element 13a is rotatable with respect to said shaft 12 and is formed with an elongated hub 18 having a lower end journaled for rotation in an aperture formed in the wall 9 and is provided adjacent said lower end with a flange 19 overlying said wall 9 as clearly illustrated in Figure 3 of the drawings.

The outer ends of the wall 9, adjacent the lower ends of the walls 8, are formed with slots 9a through which slidably extend the upper ends of bowed-shaped arms 20 comprising the lower frame section 7, the lower ends of said arms 20 being integrally connected together by a transverse portion 21. The upper ends of the arms 20 terminate in right angularly disposed fingers 22 detachably seated in recesses 23 formed in the upper face of a transversely disposed plate 24, the latter being provided with a centrally disposed opening 25 through which extends the hub 18 of the lowermost element 13a. Subjacent their upper ends, the arms 20 are formed with outwardly disposed abutments 20a which engage the under face of the wall 9 adjacent the slots 9a and thereby limit the upward movement of the lower section 7 with respect to the upper section 6.

Adjacent their lower ends the side members 8 are provided with inwardly disposed guides 26 embracing the sides of the upper ends of the arms 20 whereby to preclude relative lateral movement therebetween. Sleeved about the hub 18 is a coil spring 27, the lower end of which engages the flange 19 while the upper end engages the under

face of the plate 24 whereby said spring normally maintains the fingers 22 seated in the recesses 23 of the plate 24.

The lower ends of the shaft 12 and hub 18 extend an appreciable distance below the wall 9 and have fixed thereto drive members 28 and 28a respectively and with the drive member 28a arranged between the drive member 28 and the wall 9. The drive members 28 and 28a are fashioned with square-shaped tenons 29 and 30 respectively 10 as clearly illustrated in Figure 9 of the drawings. Obviously, upon rotation of the element 14 the drive members 28 and 28a will be rotated in opposite directions.

The tenons 29 and 30 seat within square-shaped apertures 31 and 32 respectively formed in the upper transverse bars of inner and outer agitators 33 for effecting rotation of the agitators by the members 28 and 28a, the lower ends of the agitators being pivotally and detachably connected 20 to a trunnion 34 carried on the portion 21 as clearly illustrated in Figures 1 and 2 of the drawings.

Obviously, by operating the crank arm 15, rotary movement is imparted to the agitators 33 in the usual manner for beating or whipping food stuffs and the like. By pressing the plate 24 downwardly and rotating the same with respect to the fingers 22, the arms 20 may be moved downwardly with respect to the upper frame section 6, it being understood that the slots 9a are of a sufficient length to permit the fingers 22 to pass therethrough thus enabling the lower section to be detached from the upper section. Reverse operation serves to reposition the parts in the manner disclosed in Figures 1 and 3 of the drawings. When the lower section is thus detached from the upper section, the agitators 33 may be readily removed from the lower frame section 7 for cleaning. Furthermore, if desired, the lower frame may be lowered only a sufficient distance to permit the agitators 33 to be disengaged from the members 28 and 28a.

As illustrated in Figures 10 to 14 inclusive of the drawings, I provide a frame 50 equipped with upper and lower detachable frame sections 51 and 52 respectively. The upper frame section 51 comprises a pair of spaced side walls 53 having their lower ends integrally connected together by a transverse lower wall 54 and their upper ends fashioned to define a handle 55. One of the side walls 53 is fashioned, between its upper and lower ends, with a pair of spaced arms 56 extending towards the other side wall and constituting bearings 57 through which are journaled upper 55 and lower ends of a vertically disposed shaft 58.

The upper and lower ends of the shaft 58, above and below said bearings, have mounted thereon upper and lower pinions 59 and 59a respectively meshing with a gear 60 interposed therewith 60 and coaxing therewith for driving said pinions 59 and 59a. The gear 60 is fixed to the inner end of a crank arm 61 provided with a handle 62 and which is journaled in a bearing 63 carried by one of the side walls 53.

The upper pinion 59 is fixed to the shaft 58 while the lower pinion 59a is loosely mounted on said shaft 58 for relative rotation therewith and is fashioned with an elongated hub 64 having a lower end journaled for rotation in an aperture formed in the wall 54 and is provided, adjacent said lower end, with a flange 65 overlying said wall 54 as clearly illustrated in Figure 12 of the drawings. The outer ends of the wall 54, adjacent the lower ends of the walls 53, are formed

with slots 66 through which slidably extend the upper ends of bowed-shaped arms 67 comprising the lower frame section 52, the lower ends of said arms 67 being integrally connected together by a transverse portion 68.

The upper ends of the arms 67 terminate in hook-shaped fingers 69 to which are connected the lower ends of coil springs 70. The upper ends of the springs are connected to hooks 71 formed on the side walls 53. Subjacent their upper ends, the arms 67 are formed with outwardly disposed abutments 72 which engage the under face of the wall 54 adjacent the slots 66 and thereby limit the upward movement of the lower section 52 with respect to the upper section 53. The coil springs 70 serve to normally maintain the abutments 72 in engagement with the wall 54, thus effecting connected relation between the frame sections 51 and 52.

Adjacent their lower ends the side members 53 are provided with inwardly disposed guides 73 embracing the sides of the upper ends of the arms 67 whereby to preclude relative lateral movement therebetween. The lower ends of the shaft 58 and the hub 64 extend an appreciable distance 25 below the wall 54 and have fixed thereto drive members 74 and 74a arranged between the member 74 and the wall 54. The members 74 and 74a are adapted for rotation in opposite directions with respect to each other and are fashioned with 30 square-shaped tenons 75 and 76 respectively.

The tenons 75 and 76 seat within square-shaped apertures formed in the upper transverse bars of inner and outer agitators 77 for effecting rotation of the agitators, the lower ends of the agitators being pivotally and detachably connected 35 to a trunnion 78 carried on the portion 68 as clearly illustrated in Figures 10 and 11 of the drawings.

Obviously, by operating the crank arm 61, rotary movement is imparted to the agitators 77 in the usual manner for beating or whipping food stuffs and the like. By pressing the lower section downwardly, the arms 67 are moved downwardly with respect to the upper frame section 51, it being understood that the slots 66 are of a sufficient length to permit the fingers 22 to pass therethrough, upon removal of the springs 70, thus enabling the lower section to be detached from the upper section. Reverse operation serves to reposition the parts in the manner disclosed in Figures 10 and 11 of the drawings. When the lower section is thus detached from the upper section, the agitators 77 may be readily removed from the lower frame section for cleaning. Furthermore, if desired, the lower frame may be lowered only a sufficient distance to permit the agitators 77 to be disengaged from the members 74 and 74a to permit removal for cleaning.

As illustrated in Figure 15, one of the side walls 80 of the upper frame is provided with a crank arm bearing 81 extending therethrough and to reinforce said bearing the wall 80 has a portion 82 struck therefrom with the latter formed with a depending section 83 receiving the outer end 65 of the bearing 81, thereby minimizing whipping action of the crank arm.

Without further elaboration, the foregoing will so fully explain the invention that others may, by applying current knowledge, readily adapt the 70 same for use under various conditions of service. Moreover, it is not indispensable that all the features of the invention be used conjointly since they may be employed advantageously in various combinations and sub-combinations.

It is obvious that the invention is not confined to the herein described use therefor as it may be utilized for any purpose to which it is adaptable. It is therefore to be understood that the invention is not limited to the specific construction as illustrated and described, as the same is only illustrative of the principles of operation, which are capable of extended application in advance forms, and that the invention comprehends all construction within the scope of the appended claims.

What I claim is:

1. A device of the character described, comprising, a frame equipped with upper and lower detachable frame sections, said upper frame section provided with a wall formed with slots, said lower frame section having a pair of arms extending through said slots and formed with abutments engaging said wall, resilient means mounted in said upper frame section and connected to said arms for maintaining said abutments in engagement with said wall, a pair of shafts one rotatably mounted on the other and both of said shafts rotatably mounted in said upper section and extending through said wall, agitators rotatably and detachably mounted between the lower ends of said arms and having upper walls formed with angled openings, angled members fixed to said shafts subjacent said wall and seated in said openings for effecting actuation of said agitators upon rotation of said shafts, said plate operable about said shafts for disconnection with said arms to permit lowering of said lower frame section with respect to said upper frame section for effecting withdrawal of said angled members from said openings to permit dismounting of said agitators from said lower frame section.

said angled members from said openings to permit dismounting of said agitators from said lower frame section.

2. A device of the character described, comprising, a frame equipped with upper and lower detachable frame sections, said upper frame section provided with a wall formed with slots, said lower frame section having a pair of arms extending through said slots and formed with abutments engaging said wall, a plate detachably connected to said arms, resilient means mounted in said upper frame section and securing said plate in connected relation with said arms to maintain said abutments in engagement with said wall, a pair of shafts one rotatably mounted on the other and both of said shafts rotatably mounted in said upper section and extending through said wall and plate, agitators rotatably and detachably mounted between the lower ends of said arms and having upper walls formed with angled openings, angled members fixed to said shafts subjacent said wall and seated in said openings for effecting actuation of said agitators upon rotation of said shafts, said plate operable about said shafts for disconnection with said arms to permit lowering of said lower frame section with respect to said upper frame section for effecting withdrawal of said angled members from said openings to permit dismounting of said agitators from said lower frame section.

ALBERT E. THINGLUM.
